UNITED STATES PATENT OFFICE

139,210

DESIGN FOR MANICURE SCISSORS

Lucy Cotton, Miami, Fla.

Application August 16, 1944, Serial No. 114,897

Term of patent 14 years

(Cl. D22—5)

To all whom it may concern:

Be it known that I, Lucy Cotton, a citizen of the United States, residing at Miami, in the county of Dade and State of Florida, have invented a new, original, and ornamental Design for Manicure Scissors, of which the following is a specification, reference being had to the accompanying drawing, forming part thereof.

In the drawing:

Fig. 1 is a side elevational view of manicure scissors, showing my new design.

Fig. 2 is an end elevational view.

The rear elevational view of the scissors presents substantially the same appearance as the front side, as shown in Fig. 1.

I claim:

The ornamental design for manicure scissors, as shown and described.

LUCY COTTON.
